UNITED STATES PATENT OFFICE.

CHARLES H. HUNTRY, OF ST. LOUIS, MISSOURI, ASSIGNOR OF ONE-HALF TO
THE FAY GAS FIXTURE COMPANY, OF SAME PLACE.

GASOLINE-STOVE.

SPECIFICATION forming part of Letters Patent No. 291,248, dated January 1, 1884.

Application filed July 16, 1883. (No model.)

To all whom it may concern:

Be it known that I, CHARLES H. HUNTRY, a citizen of the United States, residing at St. Louis, in the State of Missouri, have invented 5 a new and useful Improved Gasoline-Stove, of which the following is a specification.

My invention relates to improvements in gasoline-stoves; and the objects of my improvements are, first, to locate or provide the reservoir or tank to contain the gasoline at the bottom portion of the stove; secondly, to provide means to facilitate the pumping or distribution of the gasoline from its tank to any or all the pipes and their burners; thirdly, to achieve 10 during the time the burners are practically used, either separately or combinedly, a continuous pressure or steady and decisive flame; fourthly, to permit the reflow of all unused gasoline back again to its reservoir, avoiding 15 all leakage, uncleanliness, &c., and otherwise to provide an improved gasoline-stove for cooking, heat and light giving purposes, possessing the advantages of safety, reliability, and economy. I attain these objects by the 20 mechanism illustrated in the accompanying drawings, in which—

Figure 1 is a perspective view of my improved stove. Fig. 2 is a longitudinal sectional elevation, and Fig. 3 is a transverse sectional elevation.

The bottom portion of the stove consists of the main tank A, closed on all its sides, and which I call the "air-chamber."

B is the gasoline-reservoir. This is a smaller tank or vessel, closed also on all sides, and located or arranged within the air-chamber A, as shown in Figs. 1, 2, 3. The inlet of gasoline to fill the reservoir B is through the cup b, which forms part of a cock or faucet, b', that 35 has its tube communicating near top of the gasoline-reservoir, as indicated in Figs. 1, 3. The compression of air in the air-chamber is transmitted top of the gasoline in its reservoir B, and from thence the gasoline or fluid 40 is pumped or elevated and distributed through the system of pipes that have the burners. For these purposes c is a curved tube, to allow the air from air-chamber to reach top of the gasoline in its reservoir; hence one end of this

curved tube c is in communication with the 50 air-chamber A, while the other end of said tube communicates with the top of the gasoline-reservoir, as shown.

E represents an ordinary or suitable air-pump, by means whereof the air in air-chamber can be compressed. The cylinder or barrel of the pump below its piston has a small tube, e, in communication with the air-chamber A, through which the compressed air from pump enters the air-chamber. Said pump has, 55 further, an inlet air-tube, e', controlled by valve e', for fresh air to enter the pump when its piston is reciprocated to compress the air. When the pump is worked, the cock b', leading to gasoline-reservoir, is closed. It is by 60 means of the compressed air that the gasoline is forced, first, through the upright stand-pipe f, the lower end of which nearly reaches the bottom of the gasoline-reservoir, as shown, the upper end of said pipe f communicating by T 65 heads or joints to the main pipe F, that has its outer ends bent downward and closed, (see Figs. 2, 3;) secondly, from the stand-pipe F the gasoline is distributed to one or more upright pipes, g g, to which any suitable burner 70 or burners, G, can be applied, and arranged in line with the number of pot-holes h in the top of the stove. (See figures.) I is an intermediate plate or shelf, upon which dishes can be placed, warmed, &c.

80 The complete operation of the stove is as follows: The reservoir having been properly filled with gasoline, the dishes to be cooked or warmed placed on the pot-holes, the operator, by means of the pump, compresses the 85 air in the air-chamber; the compressed air from same, passing through the curved pipe into the top of gasoline-reservoir, forces its gasoline up through the vertical stand-pipe f, from thence into the main pipe F, from thence to any or 90 all the burners. In practice, but a few seconds' working of the pump is required to compress the air sufficiently and to maintain for a sufficient length of time pressure to force and keep the burners supplied, and to maintain a 95 flame without flickering, but constant, steady, and of the same quality.

Instead of using the air-pump, the equiva-

lent faucet or cock *i*, with blow-tube, (of rubber and its mouth-piece,) can be used. Said cock *i* also serves to discharge any surplus compressed air when a reflow of gasoline back 5 to its reservoir is had, or when the stove is not to be used. The stove thus serves for general purposes of cooking, heating, warming, &c.

In communication with the main pipe *F*, I have applied a further pipe, *J*, extending up- 10 right and carrying the burner *J'* top of the stove. (See Fig. 1.) This burner *J'* serves for light-giving purposes.

When the stove is not used, it will be noted that by permitting the discharge of the compressed air all the unused gasoline will reflow 15 down the same system of pipes back again into the reservoir—a feature of importance, since all leakage around the burners is thus obviated, cleanliness is insured, and the dangers 20 from fire, &c., prevented.

What I claim is—

1. The improvement in gasoline-stoves, &c., essentially consisting of an air-chamber, *A*, inclosing the reservoir *B*, to contain the gasoline, the latter reservoir being closed on all 25 sides, as shown, the curved pipe *c*, the stand-pipe *f*, and distributing-pipes with burners, and the air-pump *E*, or its equivalent, by means whereof the gasoline by compressed air can be 30 pumped or elevated to reach and be distrib-

uted to the burners, as and for the purposes set forth.

2. In combination with the air-chamber *A*, inclosing the gasoline-tank *B*, which is closed on all its sides, having inlet-cock *b'*, the air-pump or its equivalent, the pipe *c*, curved to have one end communicating with the air-chamber, the other end top of the gasoline-tank, the stand-pipe *f*, the distributing-pipes and their burners, as shown, the cock or faucet *i*, by means whereof a reflow of the unused gasoline to its reservoir is had, as and for the purposes set forth.

3. The improved gasoline-stove consisting of the main tank or air-chamber *A*, having 45 within it the gasoline-reservoir *B*, closed on all its sides, the cup, cock, and inlet-pipe leading to said reservoir *B*, the curved pipe *c*, the air-pump to compress the air, the stand-pipe *f*, the main pipe and its branches carrying 50 the burners, the top of the stove having pot-holes, all said parts combined to operate in the manner and for the purpose set forth.

In testimony of said invention I have hereunto set my hand.

CHARLES H. HUNTRY.
